[57] CLAIM

The ornamental design for a dual RJ11 connector, as shown and described.

DESCRIPTION

FIG. 1 is a perspective of a dual RJ11 connector;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The elements of FIG. 1 shown in phantom are not considered part of the claimed design. The phantom elements demonstrate the intended purpose of the dual RJ11 connector as a receptacle for a telephone plug.
